UNITED STATES PATENT OFFICE

HIRAM A. SMITH, OF PAW PAW, MICHIGAN.

DEVICE FOR USE IN ERECTING SILOS.

1,218,008.

Specification of Letters Patent.

Patented Mar. 6, 1917.

Application filed August 28, 1916. Serial No. 117,254.

To all whom it may concern:

Be it known that I, HIRAM A. SMITH, a citizen of the United States, residing at Paw Paw, Michigan, have invented certain new and useful Improvements in Devices for Use in Erecting Silos, of which the following is a specification:

This invention relates to improvements in devices for use in erecting silos.

10 The main objects of this invention are:

First, to provide an improved platform and hoisting device for use in erecting silos.

Second, to provide an improved platform and hoisting device for use in erecting silos 15 which is easily adjusted as the work progresses and one which greatly facilitates the work.

Third, to provide an improved device for use in erecting silos which is comparatively simple in structure and light in weight and 20 may be readily knocked down and compactly arranged for storage or transportation.

Further objects, and objects relating to structural details, will definitely appear 25 from the detailed description to follow.

I accomplish the objects of my invention by the devices and means described in the following specification. The invention is clearly defined and pointed out in the 30 claims.

A structure which is a preferred embodiment of my invention is clearly illustrated in the accompanying drawing, forming a part of this specification, in which:

35 Figure I is a perspective view of the upper portion of a silo in process of erection with my improved device in position thereon, the same being shown in process of adjustment.

40 Fig. II is an enlarged detail section on a line corresponding to line 2—2 of Fig. I.

Fig. III is a perspective view of the swiveled hoisting boom support.

45 Fig. IV is a perspective view of one of the post collars.

Fig. V is a side view of the post platform supporting arms and braces collapsed.

Fig. VI is a side view of the boom and its supporting struts collapsed.

In the drawing similar reference numerals refer to similar parts throughout the several views.

Referring to the drawing, the silo wall in the structure illustrated is formed of blocks or staves 1 laid to break joints, the wall being shown in process of erection. My improved device for use in erecting silos 55 comprises a center post 2, preferably a section of pipe, to which the platform supporting arms 3 are secured in a radiating relation. 60

For convenience in attaching the arms to the post is provided with collars 4 and 5 having pivot ears 6 thereon. The ends of the collars are slotted at 7, the collars being secured in place by bolts 8 arranged transversely of the slots so that the collars are securely clamped upon the post.

The supporting arms 3 are secured to the ears of the lower collar 4 by means of the pivot bolts 9. Braces 10 and 11 are secured 70 to the ears of the upper collar 5 and are detachably connected to the arms 3 by means of the bolts 12. The braces 10 are formed of angle iron while the braces 11 are formed of rods, the braces being alternate. 75 This alternate form of braces is used in order to secure lightness and rigidity.

The platform boards 13 are detachably secured to the outer ends of the arms 2 by the bolts 14. To each alternate platform 80 arm I secure a rope and pulley hoisting tackle, designated generally by the numeral 15, preferably by means of flange plates 16 secured by the bolts 14 (see Fig. II). These plates have rings 17 with which the lower 85 blocks of the tackles are engaged as are also the hanger chains 19 which are provided with hooks 20 adapted to be engaged over the wall. The tackles are provided with hooks 21 adapted to be engaged over the 90 edge of the wall. With this arrangement of parts the platform is supported within the wall at the proper height for the workmen and may be adjusted or raised as the courses are laid.

To raise the platform the tackle hooks 21 are engaged over the wall and the platform raised so as to permit the hanger hooks 95

20 being engaged and after they are engaged the platform is lowered until it is supported by the hangers.

The hoisting boom 22 is arranged in a 5 sleeve-like support 23 pivoted on the swivel pin 24 which is supported by the swivel bracket 25. At its outer end the hoisting boom is provided with a pulley 26 for the hoisting rope 27.

10 The hoisting boom is provided with a pair of struts 28 adapted to rest on the wall, the struts being provided with feet 29. By removing the bolt 30 the struts may be collapsed as shown in Fig. VI.

15 In use the boom is shifted about the wall as the blocks are laid so that the blocks may be swung to position while still supported by the hoist, the struts being diverged downwardly so that the blocks may be swung into place between them.

With my improved hoisting device and platform the work of erecting a silo is very greatly facilitated; the structure is simple and light and may be knocked down so that 25 it may be readily stored or transported.

I have not attempted to illustrate or describe various modifications which I contemplate as being desirable under certain conditions or for certain adaptations, as I believe 30 the disclosure made will enable those skilled in the art to which my invention relates to embody or adapt the same as may be desired.

Having thus described my invention, what I claim as new and desire to secure by Letters Patent, is:

1. In a structure of the class described, 40 the combination of a center post, collars secured to said post and provided with pivot ears, radiating arms pivoted to the ears of the lower collar, braces pivoted to the ears of the upper collar and detachably secured to said arms so that they may be detached therefrom and the arms and braces collapsed at the side of the post, platform members 45 removably mounted on the outer ends of said arms, hoisting tackles secured to said arms, and a hoisting boom secured to said center post.

2. In a structure of the class described, 50 the combination of a center post, radiating arms pivotally mounted on said post, braces pivoted to said post and detachably secured to said arms so that they may be detached therefrom and the arms and braces collapsed 55 at the side of the post, platform members removably mounted on the outer ends of said arms, hoisting tackles secured to said arms, a hoisting boom, and struts for said boom adapted to rest on the wall and adjustable 60 thereon.

3. In a structure of the class described, 65 the combination of a platform, a center post, a clip secured to the upper end of said center post having aligned openings, a pivot pin

having a U-shaped top mounted in said aligned openings, a collar pivotally mounted on said U-shaped top, a boom, one end of which is slidably received in the opening of said collar, a hoisting mechanism at the opposite end of said boom, and struts intermediate the collar and the hoisting mechanism for supporting said boom.

4. In a structure of the class described, 70 the combination of a platform, a center post, a clip secured to the upper end of said center post, a pivot pin having a U-shaped top mounted in said clip, a collar pivotally mounted on said U-shaped top, a boom, one end of which is slidably received in the opening of said collar, a hoisting mechanism 75 at the opposite end of said boom, and struts intermediate the collar and the hoisting mechanism for supporting said boom.

5. In a structure of the class described, 80 the combination of a platform, a center post, a clip secured to the upper end of said center post having aligned openings, a pivot pin mounted in said clip, a collar pivotally mounted on said pin, a boom, one end of which is slidably received in the opening of said collar, and a hoisting mechanism 85 at the opposite end of said boom.

6. In a structure of the class described, 90 the combination of a platform, a center post, a collar pivotally mounted on the top of said center post, a boom, one end of which is slidably received in the opening of said collar, a hoisting mechanism at the opposite end of said boom, and struts intermediate 95 the collar and the hoisting mechanism for supporting said boom.

7. In a structure of the class described, 100 the combination of a platform, a center post, a collar pivotally mounted on the top of said center post, a boom, one end of which is slidably received in the opening of said collar, and a hoisting mechanism at the opposite end of said boom.

8. In a structure of the class described, 110 the combination of a platform, a center post secured thereto, hoisting and supporting means for said platform, a hoisting boom, a support in which said boom is supported for longitudinal adjustment secured to said post, and struts for said boom adapted to 115 rest on the wall, the lower ends of said struts being spaced apart.

9. In a structure of the class described, 120 the combination of a platform, a center post secured thereto, hoisting and supporting means for said platform, a hoisting boom pivotally supported on said post, and struts for said boom adapted to rest upon the wall, the lower ends of said struts being spaced apart.

10. In a structure of the class described, 125 the combination of a platform, a center post, hoisting and supporting means for said plat-

form, a hoisting boom, a support in which said boom is supported for longitudinal adjustment swiveled on said post, and struts for said boom adapted to rest on the wall and adjustable thereon.

11. In a structure of the class described, the combination of a platform, a center post, hoisting and supporting means for said platform, a hoisting boom swiveled on said post,

and struts for said boom adapted to rest on the wall and adjustable thereon.

In witness whereof, I have hereunto set my hand and seal in the presence of two witnesses.

HIRAM A. SMITH. [L.S.]
